UNITED STATES PATENT OFFICE.

CARL J. LINDQUIST, OF NEW YORK, N. Y., ASSIGNOR OF ONE-HALF TO PAUL C. HAYES, OF TOLEDO, OHIO.

SUBMARINE DESTROYER.

1,376,105.

Specification of Letters Patent. Patented Apr. 26, 1921.

Application filed January 28, 1916, Serial No. 74,750. Renewed February 12, 1921. Serial No. 444,538.

To all whom it may concern:

Be it known that I, CARL J. LINDQUIST, a citizen of the United States of America, residing at New York city, in the county and 5 State of New York, have invented new and useful Submarine Destroyers, of which the following is a specification.

This invention relates to vessels.

This invention has utility when incorporated in readily mobile bodies, especially for 10 naval service and submarine reconnoitering.

Referring to the drawings:

Figure 1 is a side elevation of an embodiment of the device in a vessel for naval 15 service;

Fig. 2 is a fragmentary elevation of the vessel looking into the torpedo discharge tubes or ways;

Fig. 3 is a fragmentary sectional view of 20 an upper or after portion of the vessel;

Fig. 4 is a transverse section of the vessel;

Fig. 5 is a fragmentary view looking down upon the prow of the vessel;

Fig. 6 is a side elevation, with parts 25 broken away, of the prow of the vessel; and

Fig. 7 is a fragmentary detail of the torpedo discharge way and closure therefor.

The vessel comprises the inner shell or tube 1 which may be of wrought metal or boiler 30 plate material and provided with reinforcing or stiffening ribs 2. To protect the vessel from temperature change, and thereby avoid moisture precipitation upon the inner wall thereof, an insulation covering and an armor 35 jacket are provided comprising wrappings or windings of cable. The inner winding or cable 3 may be of jute or hempen rope or vegetable fiber for the insulation, the outer winding 4 being a wire cable for the armor.

40 The vessel may have a normally inclined position with its prow submerged and forwardly extending. To give the vessel stability for directing and control, brackets 5 may be provided to carry the forward rib

45 or keel 6 and the rearward rib or keel 7. The cable wrappings may snugly fit against the brackets 5. Enveloping the armor wrappings and the keels 6, 7, may be smooth sheathing 8 to minimize water resistance in 50 the vessel's travel.

Adjacent the upper end or stern of the vessel may be disposed a platform 9 carrying the bearing 10 from which rises the funnel carrying post 11 to the deck 12. Fast 55 with the post 11 is the arm 13 permitting

rotation of the funnel relatively to the deck 10. From the deck 10 but fast with the funnel 14 is the stairway 16 extending to the hatch 17, which, when the vessel is submerged may be closed to exclude water. In 60 the normal operation when the funnel is exposed, this may provide supply and exhaust air for the occupants of the vessel as well as for motor gases, in the event such type of motor is in use. 65

The usual submerging apparatus may be used.

Adjacent the lower forward end or prow of the vessel may be disposed the motor 18 having the universal joint 19 extending to 70 the downwardly inclined propeller 20. This propeller is engaged by the yoke 21 to which extend the control bars 22 from the steering wheel 23. The extensions from the keel 6, 7, serve as an enveloping housing for the 75 propeller. The shifting of the propeller by the steering wheel 23 will effect guiding of the vessel, and, as this is forward of the vessel, the vessel may be turned in a very short space, even within its own length. As 80 the axis of the propeller is downwardly inclined the driving or drawing of the vessel forward by the propeller may increase the draft of the vessel, even to a complete submergence. 85

The advantage of this device is, should there be any trouble to the driving means whereby it gets out of service, the vessel will at once rise to the surface and no danger of being entrapped in a sunken chamber 90 arises. The effectiveness of this submergence by propeller action may be varied by shifting the water ballast from a tank 24 to a tank 25 by the pumps 26, 27. With the ballast in the tank 25, the draft of the vessel 95 or its angle of inclination will be less. Such adjustment may be desirable in going into shallow water or for docking.

For observation a searchlight 28 having the lens port hole 29 may be provided. 100 Speed indicating and mileage device 30 may be provided, while inclination indicator 31 may be provided for the operators to determine the draft position of the vessel. Various decks or shelves 32 may be provided 105 with communication ways or ladders 33 therebetween.

In the event the vessel is used for naval purposes of attack or defense, torpedo ways 34 may be provided with the discharge 110

openings enlarged. A crank adjustment support 35 for the forward end of the torpedo 36 may be rocked to give the torpedo the desired direction for initial travel. The 5 torpedo way 34 may be normally closed by the door 37 actuated by the arm 38 from closed to open position. With the door 37 closed the way 34 may have the water tight door 39 removed for charging a torpedo therein, inspecting the torpedo or preparing the torpedo for discharge.

In the operation of the vessel, a small crew may readily work effectively to control the vessel's movements, as well as discharge 15 torpedoes by approaching the enemy, swinging into reverse and while fleeing effect the torpedo discharge, or discharges, as desired. The configuration is such that even when operating with the stern exposed, there is relatively a very small object 20 for target, and such target effectively armored and of a contour for readily shedding a missile by having the missile glance therefrom instead of having it embed thereinto.

The sheathing 8 may extend over the keel armor 40 on the brackets 5 while the hollow interior may be filled with insulation packing 41 to exclude water therefrom.

30 The torpedoes 36 may be released from the clips 42 before discharge. To take care of expansion of water in the chamber 34 as well as remove the water therefrom for recharging, the pipe 43 is in communication 35 with the chambers 34 and extends to the pump 44 that water may be drawn therefrom as desired.

What is claimed and it is desired to secure by Letters Patent is:

40 1. A vessel having a normally floating stern in surface travel, the remainder of the vessel being submerged, a stabilizing rib extending from the prow to the stern, and a propeller at the prow.

45 2. A vessel having a normally floating stern in surface travel, the remainder of the

vessel being submerged, and means for effecting floating and submergence of the vessel.

3. A submerged prow vessel having its 50 stern upwardly inclined, and shiftable ballast to vary the prow submergence.

4. A vessel having a normally floating stern in surface travel, the remainder of the vessel being submerged, and a ventilating 55 funnel connected to the stern.

5. A vessel having a normally floating stern in surface travel, the remainder of the vessel being submerged, a ventilating funnel connected to the stern, and a hatch for 60 closing the funnel.

6. A vessel having a normally floating stern in surface travel, the remainder of the vessel being submerged, a ventilating 65 funnel connected to the stern, and means for rotating said funnel.

7. A vessel having its axis normally downwardly inclined forwardly, said vessel having a way transversely of the vessel extent approximately horizontally disposed to 70 make an acute angle with the vessel axis.

8. A tubular submersible vessel and a condensation elimination housing for the vessel comprising continuous circularly extending means.

75 9. A submersible tubular shell vessel, an armor sheathing wrapping for the shell, and condensation elimination means spacing the armor from the shell.

10. A submerged prow tubular vessel 80 comprising a housing and a cable wrapping about said housing.

11. A submersible vessel having transversely of its axis, a torpedo discharge way, the vertical angle between said way and axis 85 being oblique.

12. A submersible vessel having transversely of its axis a relatively fixed explosive directing discharge way axis, one of said axes being inclined to the vertical.

90 In witness whereof I affix my signature.
CARL J. LINDQUIST.
